A. HEISLER.

SAFETY DEVICE FOR ELEVATORS.

APPLICATION FILED MAR. 31, 1920.

Patented Nov. 16, 1920.

UNITED STATES PATENT OFFICE.

AARON HEISLER, OF PITTSBURGH, PENNSYLVANIA.

SAFETY DEVICE FOR ELEVATORS.

1,358,734.

Specification of Letters Patent. Patented Nov. 16, 1920.

Application filed March 31, 1920. Serial No. 370,110.

To all whom it may concern:

Be it known that I, AARON HEISLER, a citizen of the United States, residing at Pittsburgh, in the county of Allegheny and State of Pennsylvania, have invented certain new and useful Improvements in Safety Devices for Elevators, of which the following is a specification.

This invention relates to safety devices for electric elevators in which a switch, carried by the cage and inserted in the electric circuit which actuates the lifting mechanism, is controlled by means of a projection arranged in the elevator well; and it consists in the novel construction and combination of the parts hereinafter fully described and claimed.

In the drawings, Figure 1 is a diagram of an elevator provided with a safety attachment according to this invention. Fig. 2 is a side view of the safety device drawn to a larger scale and showing the casing in section. Fig. 3 is a front view of the device shown in Fig. 2.

The elevator is an electric elevator of any approved construction having a cage 2 which is slidable vertically in an elevator well 3, and which is actuated by lifting mechanism of any approved kind. A casing 4 is secured in the elevator cage, and encloses a switch having a stationary and insulated contact member 5. A switch lever 6 is pivoted in the casing on a pin 7, and it carries an insulated contact member 8. The contact members are inserted in the electric circuit 9, and when in contact they permit the current to pass to the electric lifting mechanism. When the contact members are separated the circuit is broken, and the lifting mechanism is stopped, but the circuit may be so arranged that the current is only partially cut off from the lifting mechanism so that the latter is caused to operate slowly.

The switch operating mechanism on the cage is actuated by a stationary cam or projection 10 secured to one side of the well 3 at any suitable point. This cam is preferably formed of a curved spring which is curved outwardly and secured to the well at each end. A cam or eccentric 12 is mounted on a pin 14 in the casing 4, and a ratchet toothed wheel 15 is secured to one side of this cam. The cam 12 has recesses 16 in its periphery, and 17 is a spring check pawl which is secured to the casing, and which engages with the said recesses. Any other approved check mechanism may however

be used in carrying out this invention provided it will prevent the cam 12 from being improperly moved.

A lever 18 is pivoted on the pin 14, and 19 is a pushing pawl pivoted to one end of the lever and engaging with the teeth of the wheel 15. The cam 12 is arranged to one side of the switch lever 6, and engages with it when partially revolved. The other end portion of the lever 18 has a longitudinal slot 20, and 21 is a slide which is arranged horizontally, and which works back and forth on a guide 22 secured to the casing. An arm 24 projects vertically from one end portion of the slide and has a pin 25 at its upper part which engages with the slot 20. The other end portion of the slide 21 carries a roller 26 which is mounted on a pin 27.

Two curved arms 30 are provided, and are pivoted at their opposite ends to the casing 4 or other suitable support, by pins 31. The adjacent end portion of the arms 30 have slots 32 which engage with the pin 27, and the arms normally position and support the outer end portion of the slide which projects through an opening 33 in the side of the casing 4. The roller 26 engages with the cam or projection 10, and when the slide is pushed back by the cam, the switch lever is operated and the contact members are separated.

Each elevator can be provided with a series of safety devices similar to those hereinbefore described, and the cams or projections 10 are put at suitable points in the elevator well so as to stop the cage automatically at any desired levels, and to make it move slowly at predetermined points, such as when the cage approaches a landing place. The switch mechanisms are preferably arranged side by side in the cage when a plurality of them is provided, but each mechanism is arranged to work independently of the others. The ratchet toothed wheel 15 need not have teeth all around its periphery, and a single tooth engaged by the pawl 19 would be effective to open the switch. The provision of a series of teeth however enables the device to be set and adjusted to suit the requirements of different elevators, or differently located projections 10 in the same elevator shaft or well. When the elevator cage has been stopped automatically by the safety device, the elevator man in the cage re-sets the ratchet toothed wheel and pawl by hand to their original positions

in order that the cage may again be operated. The check pawl 17 prevents the switch from closing when the roller 26 is moved past the projection 10 before the cage 5 stops, which will occur on high speed elevators such as are now used in high buildings.

What I claim is:

1. In a safety device, an electric switch 10 adapted to be secured in an elevator cage and provided with a pivoted switch lever, a stationary projection adapted to be secured in the elevator well, a cam for moving the said lever to open the switch, a cam 15 operating lever pivoted concentric with the cam, a pawl and ratchet mechanism operatively connecting the said cam operating lever with the cam, a horizontal slide provided with a roller at one end for engaging with the said projection and having its other 20 end operatively connected with the cam operating lever, and a spring which normally projects the said slide so that its roller will engage with the said projection.
2. In a safety device, an electric switch 25 provided with a pivoted operating lever and adapted to be carried by an electric

cage, a stationary projection adapted to be secured in the elevator well, a revoluble cam for operating the switch lever, a toothed wheel secured to the said cam, a lever pivoted concentric with the toothed wheel and provided with a pawl for engaging with its teeth, and a horizontal slide which is pushed back by the said projection and which operates the last said lever.

3. In a safety device, an electric switch provided with a pivoted operating lever and adapted to be carried by an elevator cage, 40 a stationary projection adapted to be secured in the elevator well, a revoluble cam for operating the switch lever, a horizontal slide which is pushed back by the said projection and which is operatively connected with the said switch lever, a guide for the inner end portion of the slide, and two pivoted arms having their adjacent end portions pivotally and slidably connected with the outer end portion of the said slide and 45 normally holding it in position to be engaged by the said projection.

In testimony whereof I have affixed my signature.

AARON HEISLER.
